ILLUMINATED DOUBLE-FACED MAKE-UP MIRROR

Tadao Ishikawa, Saitama, and Toshiaki Tokuda, Gunma,
Japan, assignors to Sanyo Electric Co., Ltd., Osaka,
and Tokyo Sanyo Electric Co., Ltd., Gunma, Japan

Filed Aug. 20, 1970, Ser. No. 24,606

Claims priority, application Japan July 9, 1970

Term of patent 14 years

Int. Cl. D28—03

U.S. Cl. D86—10

FIG. 1.

FIG. 2.

FIG. 3.

FIG. 4.

FIG.5.

FIG.6.

FIG.7.

FIG. 1 is a front view of an illuminated double-faced make-up mirror; showing our new design;

FIG. 2 is a rear view thereof;

FIG. 3 is a top view thereof;

FIG. 4 is a bottom view thereof;

FIG. 5 is a left side view thereof;

FIG. 6 is a right side view thereof;

FIG. 7 is a front perspective view thereof.

The reflecting surfaces illustrated in FIGS. 1, 2, 3 and 7 are rotatable about a horizontal axis on the shafts illustrated with one face thereof being plane and the other face being concave.

We claim:

The ornamental design for an illuminated double-faced make-up mirror, substantially as shown and described.
